UNITED STATES PATENT OFFICE.

ARTHUR G. WATKINS, OF MECHANICSBURG, PENNSYLVANIA, ASSIGNOR OF ONE-FOURTH TO DAVID J. BEITZEL, OF MECHANICSBURG, PENNSYLVANIA.

SHADE OR CURTAIN FIXTURE.

1,041,537.

Specification of Letters Patent.

Patented Oct. 15, 1912.

Application filed February 16, 1912. Serial No. 677,890.

To all whom it may concern:

Be it known that I, ARTHUR G. WATKINS, a citizen of the United States, residing at Mechanicsburg, in the county of Cumberland and State of Pennsylvania, have invented new and useful Improvements in Shade or Curtain Fixtures, of which the following is a specification.

This invention relates to improvements in window shade or curtain fixtures, the primary object of the invention being to provide a fixture composed of relatively stationary and adjustable attaching and supporting members, which will permit of a relative adjustment between the pair of fixtures secured to the window frame so that shades or curtains of different widths may be supported, the construction being such that the adjustable members may be adjusted in a ready, quick and convenient manner without the necessity of shifting the position of the relatively stationary members on the window frame and thereby marring or injuring the woodwork.

A further object of the invention is to provide a shade or curtain fixture which provides for the firm clamping of both the stationary and adjustable members in position, thus obviating possible casual displacement of the adjustable members and enabling comparatively heavy shades or curtains to be supported without the necessity of employing heavy or cumbersome fixtures.

The invention consists of the features of construction, combination and arrangement of parts, hereinafter fully described and claimed, reference being had to the accompanying drawings, in which:

Figure 1 is a front view of a window frame showing the application of the invention. Fig. 2 is a transverse section through one of the jambs of the frame, showing the fixture thereon in longitudinal section. Fig. 3 is a vertical transverse section on the line 3-3 of Fig. 2. Fig. 4 is a perspective view of a modified form of fixture.

Referring to the drawings, 1 designates a window frame, to the opposite sides of which are secured fixtures embodying my invention. Each of these fixtures comprises comparatively stationary and adjustable attaching and supporting members 2 and 3.

The member 2 consists of an oblong rectan-

gular bracket plate provided at its ends with integral perforated ears 4 for the passage of screws or other suitable fastenings 5 to secure the same in position. This plate is provided with a longitudinal recess 6, which opens through its rear side and is substantially V-shaped in cross section, having upper and lower forwardly converging beveled walls 7. The plate is also provided in its front with a longitudinal guide slot 8 of less length than the recess and substantially coextensive in width with the forward or contracted portion of the recess. The rear faces of the ears 4 are flat to form abutting surfaces to rest against the window frame, and the rear face of the plate is provided with longitudinal abutting surfaces 9 flush with the rear faces of the ears and also adapted to bear flatly against the window frame.

The fixtures are employed as usual in pairs for supporting the ends of a shade or curtain roller at opposite sides of the window frame, the attaching members 2 being extended longitudinally across the face of the frame and secured firmly in position by the screws or fastenings 5.

Each member 3 comprises a bracket arm 10 having a shank 11 projecting through and movable in the slot 8 and carrying at its inner or rear end a lug 12 which is enclosed wholly within the recess 6 and is V-shaped in vertical section to conform to the shape of said recess. This lug is provided with beveled upper and lower surfaces 13 to bind against the beveled walls 7 of the recess and with a rear flat abutting face 14 normally lying flush with the abutting surfaces 9 to bear therewith against the face of the window frame. Thus when the member 2 is fastened in position the member 3 will be firmly held in adjusted position against shifting movement, as the face 14 of the lug will bind against the window frame, while the binding surfaces 13 of the lug will bear against the coating binding surfaces 7 of the member 2.

Where the members 3 are employed for supporting a shade roller the bracket portions 10 thereof will be respectively provided with a round opening to receive the journal at one end of the roller and a rectangular slot or opening to receive the rectangular end of the spring shaft at the opposite end of the roller. In order to relatively

adjust the brackets of the supporting members 3 to suit any width of shade roller, it is simply necessary to relax one or both securing screws 5 of each member 2, whereupon 5 the pressure upon the lug 12 will be released, permitting it to be adjusted as desired in the recess, after which by tightening the screws the lug will be bound firmly in adjusted position. Hence it will be seen 10 that after the members 2 are once applied in position, no shifting motion or application of the same at different points on the window frame is required for adjusting the fixtures to support different lengths of 15 rollers, whereby marring of or injury to the woodwork is avoided.

In Fig. 4 I have shown a form of supporting member adapted for hanging curtain rollers. In this embodiment of the invention, a U-shaped bracket member 15 is provided to receive the roller and is formed with a shank 16 carrying a lug 17 of the structure before described and adapted for use with an attaching plate of the character 25 disclosed. This supporting member is provided with a bracing arm 18 projecting downwardly and rearwardly at an angle therefrom and carrying at its lower end a bearing plate 19 adapted to engage the face 30 of the frame below the lug and attaching member. This bearing member 19 is preferably provided with push pins 20 adapted to be forced by a gentle pressure into the window frame to retain it in position, allowing 35 it, however, to be detached by a slight outward pull when the lug 17 is free for movement in the recess of the attaching member so that the supporting member may be adjusted as occasion requires. It will, of 40 course, be understood that in order to permit the arms 16 and lugs 17 to be applied to the bracket, the lug is initially formed independent of the arm, and after said arm is passed through the slot 8 in the bracket, 45 the lug is threaded upon, soldered to or otherwise connected with the arm. The arms 18 of the supporting members employed brace the same firmly from the window frame, allowing comparatively heavy 50 curtain rolls to be supported without employing a heavy or cumbersome type of supporting member. The construction of the attaching member and lug also enables shade supporting members of light weight 55 and comparatively small size to be used for

effectually supporting heavy shade rolls, as will be readily understood.

Having thus described the invention, what I claim as new is:—

1. A fixture of the character described 60 comprising an attaching plate having apertured ears at its ends, a longitudinal slot in its front wall between said ears, a longitudinal recess opening through the rear face of said plate, said recess being V-shaped in 65 cross section and communicating at its front with said slot and providing beveled top and bottom binding surfaces, the rear face of the plate and rear faces of the ears providing bearing surfaces flush with each 70 other and adapted to lie snugly against the window frame, fastening members adapted to be passed through the apertured ears to clamp the attaching plate in position, and a supporting member having a shank passing through and adjustable in said slot and carrying a lug wholly inclosed within and adjustable in said recess, said lug having beveled binding surfaces to engage the beveled faces of the recess and a flat rear bearing 80 face bearing against the wall of the window frame, said bearing face normally lying flush with the bearing faces of the attaching plate when said plate is fully secured in position, whereby the lug will be clamped in place 85 and whereby upon loosening one of the fastening members said lug may be adjusted and again clamped by tightening said fastening member.

2. A fixture of the character described 90 comprising an attaching plate having end attaching means and provided in its front with a longitudinal slot and in its rear with a longitudinal recess, said recess being provided with beveled binding walls, and a 95 supporting member having a shank adjustable in said slot and carrying a lug adjustable in said recess and provided with co-acting beveled binding walls, said member being also provided with a bracing arm 100 terminating in a bearing plate having projecting pins adapted to be pressed into the face of the window frame.

In testimony whereof I affix my signature in presence of two witnesses.

ARTHUR G. WATKINS.
